JAW ASSEMBLY FOR WRENCHES OF THE
STILLSON TYPE

Brereton Roberts, Cimla, South Wales

Application October 29, 1948, Serial No. 57,290
In Great Britain November 5, 1947

3 Claims. (Cl. 81—126)

1

The present invention relates to wrenches of the Stillson type and more particularly has reference to a jaw assembly for use with such wrenches.

An object of the invention is the provision of an adjustable wrench of the Stillson type which is provided with, or which is adapted to be fitted with, jaws which completely embrace the object gripped.

Yet another object of the invention is the provision of a novel fixed and movable jaw assembly which is adapted to be fitted to a wrench of the Stillson type.

Further objects of the invention will become apparent from the following description taken in conjunction with the accompanying drawing.

In the drawing:

Figure 1 is a side view of a wrench constructed in accordance with the invention;

Figure 2 is a section taken on the line II—II of Figure 1;

Figure 3 is a view similar to Figure 1 showing a modified form of wrench;

Figure 4 is a horizontal sectional view taken along the line 4—4 of Figure 3, the view looking in the direction of the arrows, and

Figure 5 is a vertical sectional view taken along the line 5—5 of Figure 3, the view looking in the direction of the arrows.

Referring first to Figures 1 and 2, the wrench comprises a handle 1, one end of which is enlarged at 2 and is formed with a serrated work-engaging or gripping face 3, these parts forming the fixed jaw of the wrench.

The handle 1 is formed with a transverse bore which is offset with respect to the face 3 and which receives a pivot pin 4. This pin 4 serves for the attachment to the handle 1 of a connecting structure 5 which carries an adjustable jaw member 6.

In this construction the connecting structure 5 consists of two separate cheek pieces 7 which are spaced from each other, being pivoted one on each end of the pivot pin 4 on opposite sides of the handle 1.

The adjustable jaw member 6 comprises a shank 8, which is slidably fitted between the cheek pieces 7, and a projecting jaw part 9 which is formed with a serrated work-engaging or gripping face 10. The shank 8 is formed with longitudinal grooves 11 on its opposite sides, which grooves receive correspondingly shaped ribs 12 formed on the inner faces of the cheek pieces 7. The shank 8 is also formed on its front and back edges with thread-engaging teeth 13 which may be of generally square section.

2

The cheek pieces 7 are of L-shape as shown in the drawing, the shorter arms 14 being drilled to receive the pivot pin 4 and the longer arms 15 being adapted to engage the shank 8. The arms 15 of the cheek pieces 7 are of somewhat smaller section than the arms 14, being separated from the latter by shoulders 16; the outer surfaces of the arms 15 are of arcuate shape as is shown at 17 in Figure 2. At their free ends the arms 15 are provided with outwardly projecting lips 18.

Surrounding the shank 8 and the arms 15 of the cheek pieces 7 is an annular adjusting member or ring 19 which is preferably knurled on its outer surface. This member is internally threaded to engage the teeth 13 on the shank 8. It is rotatable about the cheek pieces 7 but it is prevented from moving longitudinally on them (except possibly for a small amount of play) since at one end it is engaged by the shoulders 16 of the cheek pieces while at its other end it is engaged by the lips 18.

To assemble the wrench the cheek pieces 7 are fitted within the adjusting member 19 before the latter is threaded on the shank 8. By turning the member 19, the distance between the work-engaging faces 3 and 10 can be adjusted as required. The wrench is used in the same manner as an ordinary Stillson wrench.

It will be apparent that the invention provides a wrench the parts of which are easy to manufacture and assemble while the complete wrench is of strong and robust construction without being unduly heavy.

For certain purposes it is convenient to have a wrench the jaws of which completely embrace the work and the present invention provides means for achieving this. Figure 3 of the drawing shows an adjustable wrench which is similar to that shown in Figures 1 and 2 except that the adjustable jaw member 6 has been replaced by a jaw assembly 26 comprising both fixed and adjustable jaws which together completely surround the work held between them.

The wrench shown in Figure 3 comprises a handle 1 and a connecting structure 5 which are identical with those shown in Figures 1 and 2, the handle having an enlarged end 2 and a serrated face 3 and the structure 5 comprising a pair of cheek pieces 7 and an annular adjusting member 19, the cheek pieces 7 being pivoted to the handle 1 by means of a pin 4.

The jaw assembly 26 comprises a shank 28 which is formed with thread-engaging teeth 33 and with longitudinal grooves 31. The shank 28 is in fact similar to the shank 8 and is fitted be-

tween the cheek pieces 7 and within the adjusting member 19 in an exactly similar manner.

The shank 28 carries a head 29 which is of generally U-shape and is formed with a serrated work-engaging face 30. A bridge 40 connects the end of the U-shaped head 29 with the shank 28.

This bridge 40 is formed with a rectangular slot 41 in which is slidably mounted the leg 42 of a jaw member 43. One end of the member 43 is enlarged and is formed with a serrated work-engaging face 44 of arcuate form, while at its other end the leg 42 is provided with a foot 45 the base 46 of which is engaged by the face 3 of the handle 1.

Preferably, the jaw member 43 is forged from a single piece of steel, while the bridge 40 is constructed of two side parts which are assembled about the leg 42 of the member 43 and are secured by welding, riveting or other means to the shank 28 and to the end of the head 29.

The wrench shown in Figure 3 is used in a similar manner to the wrench of Figures 1 and 2 except that the work is gripped between the faces 30 and 44 instead of between faces 10 and 3. Owing to the engagement between the face 3 of the handle and the base 46 of the foot 45 the distance between the faces 30 and 44 can be adjusted as desired by turning the adjusting member 19. Also when the wrench is applied to the work and a turning effort is applied to it in the usual manner the faces 30 and 44 are forced towards each other to grip the work more tightly in a similar manner to the faces 10 and 3 of the first construction. In fact when the wrench is in use the face 44 constitutes the fixed jaw face corresponding to the face 3; the member 42 then acts in effect as an extension of the handle 1.

Other modifications are also possible. Thus, instead of providing the ribs 12 on the cheek pieces 7 and forming the shank 8 with grooves 11 as shown, the grooves could be formed in the cheek pieces and the ribs provided on the shank.

While I have described preferred embodiments of my invention it is to be understood that these are given by way of example only. I do not desire to be limited thereto but wish to avail myself of all modifications coming within the spirit of the invention as set forth in the appended claims.

I claim:

1. An adjustable wrench comprising a handle having a working face at one end thereof, an

intermediate jaw member separate from said handle and provided with a working face adapted to be disposed upon the working face of the handle, a connecting structure, means pivoting said connecting structure on said handle, an adjustable outer jaw member having a shank and a jaw part formed with a work-engaging face, said shank being formed with thread-engaging elements and being slidably mounted in said connecting structure, means mounting said intermediate jaw member on said adjustable outer jaw member for relative movement therebetween while supporting said intermediate jaw member on said handle, a nut embracing said shank and said connecting structure, said nut having an internal thread which engages with said thread-engaging elements, and means swivelling said nut on said connecting structure whereby rotation of said nut adjusts the work-engaging face of said outer jaw member either toward or away from said intermediate jaw member.

2. An adjustable wrench as defined in and claimed by claim 1, further characterized in that said intermediate jaw member is slidably mounted in said adjustable outer jaw member.

3. An adjustable wrench as defined in and claimed by claim 1, further characterized in that said adjustable outer jaw member comprises an inverted U-shaped part having legs and an arcuate portion, said work-engaging face being formed on an inner side of said arcuate portion, a member bridging the legs of said U-shaped part, and said intermediate jaw member being slidably mounted in said bridge member.
